Primary Examiner — Sandra Snapp*Assistant Examiner* — Altaira J Swangin(57) **CLAIM**

The ornamental design for a decanter, as shown and described.

DESCRIPTION

FIG. 1 is a top, front, left side perspective view of a decanter showing my new design;

FIG. 2 is a front elevation view thereof, the rear elevation view being a mirror image of the front elevation view;

FIG. 3 is a right side elevation view thereof, the left side elevation view being a mirror image of the right side elevation view;

FIG. 4 is a top plan view thereof;

FIG. 5 is a bottom plan view thereof; and,

FIG. 6 is another top, front, left side perspective view thereof showing the bottle body separated from the base. The broken lines in the drawings illustrate portions of the decanter that form no part of the claimed design.

1 Claim, 6 Drawing Sheets(56)
